COMMUNICATION AND POSTING SYSTEM

Harold F. May, Valley Stream, and Joseph C. Marshall, Baldwin, N. Y., assignors to The Teleguide Corporation, New York, N. Y., a corporation of Delaware

Application January 15, 1944, Serial No. 518,370

15 Claims. (Cl. 177—353)

This invention relates generally to communication and posting systems for displaying information or data in regard to a number of different items by means of groups or rows of indicators which are automatically and selectively actuatable or settable in response to incoming signals to display information or current changes in information in regard to the items posted, and is particularly applicable, although not limited, to a system for the transmission, recording and posting of data on announcement or bulletin boards relating to air traffic control information, in which the signals representing the information thus posted may be transmitted either from a local transmitter or from wire or radio transmitters remotely situated with respect to the receiving, posting and recording apparatus, which remote transmitters may be located at ground stations or within aircraft in flight. The system disclosed herein is an improvement over the communications and posting system disclosed in the patent to J. C. Marshall and M. L. Haselton, No. 2,246,449, issued June 17, 1941.

In systems for recording and posting flight plans and flight progress reports of aircraft and other messages relative to the control of aircraft, hereinafter referred to as air traffic control systems, the information thus posted on the bulletin or announcing board usually relates to numerous flights, and the items posted usually are arranged in groups according to the various "marker" or "fix" classifications, as explained in the aforesaid Marshall et al. patent, and preferably are arranged within each fix group in accordance with the expected or estimated time of passage or arrival of the aircraft at the various recording or marker points en route and at the airport. The flight data posted may have to be changed from time to time during the progress of the flights as the result of conditions affecting the progress of aircraft, such as poor visibility, ice, changes in the direction and velocity of the wind, the necessity for blind landings, and other emergency conditions.

The information posted may comprise numerous data, such as the flight designation symbols followed by a section number, if any; information as to the direction of the various flights; the airway traffic controller's estimated time when the aircraft will pass over or land at certain marker points on the flight route; the time the aircraft actually passes over or lands at each marker point; the expected approach time when the pilot may receive instructions to start his

approach to a landing field; proposed altitudes at which a clearance has been issued to cross each marker or flight path; the altitude at which the aircraft actually crosses the various markers; and the landing sequence number assigned to landings under instrument conditions. In addition to the foregoing, other information may be posted on the flight progress display boards, such for example as an indication that a clearance through a marker or fix has been issued; an indication of a flight over the airport; an indication of a stop en route, and the expected approach time, or that if a delay is encountered the degree of such delay is unknown; and an indication that an aircraft has been cleared to the airport control tower or range station so that there will be no delay in landing.

Local communication facilities comprising known telephone or telegraph wire or radio equipment may be employed to establish communication between the air line company's dispatch offices and the various aircraft, airport control towers, the local communications operator of the airway traffic control, government regulating bureaus, local military operations offices, if any, and other airports.

One of the objects of the invention is an improved system and equipment for automatically receiving, recording and posting the desired data in regard to various items, particularly aircraft or other vehicles, which equipment is responsive to incoming signals for automatically recording and posting current or changed information in regard to the various aircraft or other items.

Another object is a posting or announcing system, and particularly a system adapted for flight control, which utilizes two boards having indicators carrying substantially the same information, or on which certain information is duplicated, one of which boards is a record board in which the flights or other items may be recorded and posted in random order and the other an announcing or display board in which the various flights or other items may be displayed and maintained in any desired serial order or sequence.

Still another object is the provision of means operable at will for automatically rewriting the information on the display board in accordance with the data stored on the record board, in which a multiplicity of rows of indicating devices in the display board may simultaneously or concurrently be rewritten by a multiple row sequencing operation.

An additional object is an improved arrange-

ment whereby the order in which the items are displayed on the display board may readily be changed at will in accordance with a predetermined chronological sequence.

Another object is a system in which the positions of the items displayed on the display board respectively are determined by the settings of new position posting units associated with each row of indicators in the record board.

A further object is improved flight or item locator apparatus in which all flight or item identification storage devices are compared simultaneously with the identification data of signals incoming to the locator apparatus.

Still another object is a system of the character described in which the information recorded in the record board may automatically be transferred to the display board without affecting or changing the settings of the recording devices in the record board, whereby the record board provides a convenient means for checking the accuracy of the information displayed at any time by the display board.

An additional object is means for recording the present location of the flights or other items posted on the display board and recording means concurrently operative for preselecting the new positions to which the information on the display board may subsequently be transferred.

Still another object is means for taking the information stored in the record board in a sequence determined by the new position recording devices and temporarily storing the same, and subsequently resetting a multiplicity of rows of indication devices concurrently or simultaneously in the display board, to minimize interference with the displayed record.

Various other objects, advantages and improvements will be apparent from the following detailed description of one illustrative embodiment of the invention, taken in connection with the accompanying drawings, in which:

Fig. 1 is a view, in diagrammatic form, of certain transmitting and receiving apparatus including seeker mechanism suitable for use with the system of the invention;

Fig. 2 shows a local keyset in diagrammatic form adapted for use with the system;

Fig. 3 shows various selecting, distributing and indicator pulsing apparatus, together with new position recording indicators associated with rows 01 to 14 of indicators of the record board;

Fig. 4 is a view of other distributor apparatus, together with new position recording indicators associated with row 00 of indicators in the record board, and new position code translating relays and sequence collection switching apparatus;

Fig. 5 represents diagrammatically, a plurality of rows 00 to 14 of indicators in the display board;

Fig. 7 shows flight identification code translating relay apparatus and certain selection and sequence apparatus employed;

Fig. 8 illustrates a distributor and associated relays employed for sequencing the items posted on the display board;

Fig. 9 shows diagrammatically various data recording indicators employed in the record board, together with associated code translating relays;

Fig. 10 shows various storage relays employed in connection with the sequencing operations;

Fig. 11 is a diagram showing the arrangement of the various sheets of drawings illustrating the system;

Fig. 12 is a detail of the mechanical latching feature employed in connection with the present position recording relays shown in Figs. 6 and 7; and

Fig. 13 is a diagram showing various elements of the system, including the record board and flight progress display board employed.

In the specific embodiment of the invention illustrated herein, data in regard to the movements of a number of aircraft within a given area of a terminal or other flight control zone are recorded, and preferably are visually posted, on a record board, shown in the upper right hand portion of Fig. 13, and are displayed in predetermined sequence on the display board shown in the lower right hand portion of the figure. Rotatable indicators, which are arranged in horizontal rows, or tiers designated 00 to 14 preferably are employed as the recording and display devices. Each row of indicators is identified with a certain flight and is adapted to display the flight identification number and flight information or data, for example, the time at which the aircraft passes or reaches a particular location or marker point, referred to in the art as a "Fix," and the altitude of the aircraft at the various Fix points, and also any additional information which it may be desired to record or post on the record and display boards.

While the flights may be recorded or stored in the record board in random order, it is highly desirable that in the flight progress display board the flights and information in regard thereto may be displayed in a desired chronological sequence, the indicators also being arranged in groups corresponding to the different Fix points to which they relate, such as Fix 1, Fix 2 and Fig. 3. Both the record board and the flight progress display board may be located at an air traffic control center, such as an airport, where the flights terminate or traverse a predetermined area associated with or controlled by the airport, and are posted on the display board by means of indicators so as to be visible at all times to the airway traffic personnel or others interested in the progress of the flights thus posted.

At the traffic control center a local keyboard and mechanism associated therewith is provided for initially setting up on the record board, and if desired, on the display board, information such as the flight designations, and the estimated time and altitude and other data in regard to the various aircraft at the several fixes or marker points, the keyboard also serving to initiate multiple row sequencing of the display board to enable rearrangement of the order or sequence in which the flights are displayed.

The signals incoming from the various places for posting the record board and the display board may be of any suitable type. Usually, and in accordance with conventional telegraph practice, permutation code signals, for example, five-unit code signals, are employed, which signals may be initiated either at the station 101, Fig. 1, and transmitted by wire or line L1 to the receiving equipment, or the signals may be transmitted by radio transmitting apparatus, such as teleprinters situated in the aircraft, while the aircraft is in flight and thus transmit signals which are received by radio apparatus, Fig. 1, situated at any suitable location. Such radio receiving apparatus may comprise audio frequency filters,

each associated with an aircraft and tuned to the frequency of the audio frequency generator of the associated aircraft, each of the filter circuits being connected by a conductor such as L2 or L3 to distributors 105 and 106 for causing the received messages to be stored by reperforators 103 and 109, and thereafter to be retransmitted from perforated tapes t2 and t3 to transmitters TTR2 and TTR3 for controlling the posting and display boards, as set forth in the aforesaid Marshall et al. Patent No. 2,246,449. Any other suitable method of transmitting and receiving signals for controlling and actuating the recording and posting apparatus may, of course, be employed.

Posting the record board and the display board by incoming signals

The manner in which signals received from one of the transmitting stations, for example, from teleprinter 101 over the line L, Fig. 1, are employed to control the operation of the time and altitude record board and display board indicators TT, TU, AT and AU shown in Figs. 5, 9 and 13, and the monitor printer MP, Fig. 1, is generally as described in the Marshall et al. patent except that the circuit is modified in certain respects in accordance with the instant invention. Assume, for example, that the record board (Figs. 3, 4, 6, 7, 9 and 13) and the display board (Figs. 5 and 13) are located at the Washington Airport, and that the operator at station 101, which may be located at one of the fix points, for example, Philadelphia, which is designated as Fix 1, desires to transmit to the Washington Airport information in regard to a flight identified as No. 34, which is passing over the Philadelphia fix at 1:35 p. m. at an altitude of 4500 feet. This information will be received and printed on the multiplex printer MP, Fig. 1, and also posted on the record board and display board, Fig. 13, at the Washington Airport.

The operator at station 101 at Fix 1 actuates the keys of his teleprinter keyboard and sends numerical and functional characters comprising the message in the following order: 3 4 1 3 3 5 space space 3 4 1 2 4 5 and end-of-message. The first two characters 3 and 4, represent the flight identification number 34, the third character 1 the fix selecting number corresponding to Philadelphia, the fourth character 3 is the range or selecting signal for the time posting indicators, the fifth and sixth characters 3 and 5 are the tens and units digits, respectively, of the time, and the two spacing signals are interposed between the first and second part of the message transmitted. The characters 3 and 4 following the second space signal again represent the flight identification number, and digit 1 the fix number, 2 the range or selecting signal for the altitude posting indicators, characters 4 and 5 the thousands and hundreds digits of the altitude, and the end-of-message signal, usually transmitted by the key L of the printer keyboard.

The keyboard printer 101 may be any of the well-known types such as shown in the Martin et al. Patent 1,745,633 or in the Noxon et al. Patents 2,231,215 and 2,252,232. These start-stop printers send and also record the transmitted signals on a tape, which signals are composed of marking and spacing units comprising a start impulse followed by a permuted group of five marking and spacing impulses in various combinations representing the character transmitted, each group being terminated by a rest impulse

which is of opposite line condition to that of the start impulse. The operation of the flight identification key 3 causes a start impulse to be applied to the line L, thereby setting the receiving distributor 104 into operation. This impulse is followed by the code signal for the number 3 followed by a rest impulse. The operation of distributor 104 causes the code units of the signal received to be transmitted over five conductors to a reperforator 107, a sixth conductor 6 of the group serving to operate the punch magnet of the reperforator. The reperforator perforates the tape t issuing therefrom in accordance with the signals received, and steps the tape ahead 15 into position for the next succeeding perforating operation corresponding to the second digit of the flight identification number. Any of various known types of perforators may be employed, for example, as disclosed in the patent to Hoover 2,252,852 or a printer reperforator such as disclosed in the Dirkes et al. Patent 2,193,809. Since the permutation signal for the digit 3 has the code unit 1 only marking in character, conductor 1 has marking potential applied thereto and the 25 remaining conductors 2 to 5 have spacing or no-current condition applied thereto, thereby causing a single perforation to be made in the tape at this time corresponding to the numeral 1.

The conductors 1 to 5 are connected by means 30 of a cable 110 to the windings of four end-of-message relays EM1 to EM4 of the group B, the conductors 1 and 2 of cable 110 being connected to the left hand and inner operating windings, respectively, of relay EM1, and conductors 3, 4 and 5 of the cable are connected to the operating windings of relays EM2, EM3 and EM4, respectively. The application of a marking signal to conductor 1 of the cable causes relay EM1 to operate over a circuit from ground at its left hand 40 winding to marking battery applied to the conductor by the distributor 104. Relay EM1 locks by means of its right hand make contact and armature 111 to battery on conductor 112 supplied by the break contact of the sixth pulse relay 114 of the distributor 104. The operation of relay EM1 is without effect at this time, the relay releasing upon the subsequent operation of the sixth pulse relay.

In a similar manner the signals corresponding 50 to the digits 4, 1, 3, 3 and 5 are received and stored in the perforated tape t1, the relays EM1 to EM4 operating in code combination to read the character each time a digit or a character signal is received. The two spacing signals immediately following the digit 5 cause the tape to be stepped ahead twice in known manner. Signals corresponding to the digits 3, 4, 1, 2, 4 and 5, respectively, follow the two space signals and are stored in the tape t1 and also cause the operation of the end-of-message relays EM1 to EM4 in code combination corresponding to each of the digits stored in the tape.

Immediately following the signal for the digit 5 is the end-of-message signal having the code units 1, 2 and 4 spacing and units 3 and 5 thereof of marking in character. This signal causes relays EM2 and EM4 to operate and lock to battery on conductor 112, and relays EM1 and EM3 to remain unoperated. Ground at armature 60 114 and break contact of relay EM1 is extended to armature 115 and make contact of operated relay EM2, armature 116 and break contact of unoperated relay EM3, armature 117 and make contact of operated relay EM4, and thence by conductor 118 through the winding of relay L to

grounded battery, thereby causing relay L to operate and lock over its make contact and armature 120, conductor 121, and break contact and armature 122 of release relay RS5 to ground. Conductor 121 also extends, through a conductor 124, to contacts 125 of a tight-tape switch or auto-control AC which, when a complete message is stored in the tape loop between the reperforator and tape transmitter, are closed, thereby applying ground to the locking circuit of the relay L holding the relay operated.

The operation of relay L, at its armature 126 and break contact, interrupts the circuit to terminals 3 and 7 of the bank A of the rotary seeker switch SS, and at the make contact of its armature 126 relay L applies ground to the corresponding armatures 126 and break contacts of the relays K, R₁ and R₂, to terminals 1, 2, 4, 5, 6 and 8 of bank A of the seeker switch SS. If it be assumed that the switch wipers are resting on their terminals 1 at this time, ground at terminal 1 is extended by way of the switch wiper of bank A, break contact and armature 128 of the seeker stepping magnet SSM, and thence to grounded battery, thereby causing the stepping magnet to operate on self-interruptions and advance the wiper for the bank A thereof to its terminal 3 which has ground removed therefrom by the operation of relay L.

With the wipers of the banks A, B and C of the switch SS resting on their terminals 3, a circuit is completed from battery at the lower outer armature 129 and make contact of relay L, conductor 3 of cable 130, to the upper operating winding of transmitter-connecting relay TC, conductor 131, terminals 8 and 3 of bank C of the seeker switch and wiper thereof, conductor 132, and thence by way of conductor 7 in cable 133. Cable 133 extends to Fig. 4, and conductor 7 thereof is connected to the winding of a start magnet SM1 associated with the rotary distributor DR1, and thence by way of conductor 4 in cable 401 to the lower break contact and armature 700 of a sequence start relay SST, Fig. 7. From the armature 700 the circuit continues by way of conductor 1 in cable 401 and cable 133, Figs. 3 and 4, to the stop segment 1 of the segmented ring 1 of rotary distributor DR2, and thence through the brush b to the solid ring 2 of the distributor to ground, thereby operating the transmitter-connecting relay TC, Fig. 1, and the start magnet SM1, Fig. 4. The operation of relay TC, Fig. 1, connects the transmitting tongues and the tape step magnet TS of the tape transmitter TTR1, in multiple with the monitor printer MP, through conductors 1 to 6 of cable 135, and through cable 140 to the five solid rings 2, 4, 6, 8 and 10 of the rotary distributor DR1, Fig. 4. Conductor 6 is connected to the even-numbered segments 2, 4, 6, 8, 10 and 12 of the segmented ring 11 of distributor DR1. Relay TC, Fig. 1, locks from grounded battery through its lower winding and contacts 7, and conductor 141, to the middle break contact 302 and armature 330 of release relay REL, Fig. 3, to ground.

Operation of distributor DR1

The start magnet SM1, Fig. 4, having operated in series with transmitter-connecting relay TC, releases the brush arm of distributor DR1, thereby setting the distributor in operation. The engagement of brushes b1 to b5 of the distributor with their corresponding segments 2, closes circuits from the tongues of the tape transmitter TTR1, Fig. 1, through conductors 1 to 5 of cable

140, and through conductors 1, 7, 13, 19 and 25 of cable 402, Fig. 4, to the grounded windings of the 1st digit identification storage relays 111 to 115, Fig. 6. Since in the example assumed, the first digit of the flight identification number is the digit 3, which has one marking and four spacing pulses, the transmitting tongue 1 of the tape transmitter TTR1 is the only tongue in closed position, thereby causing relay 111 only of the 1st digit identification relays to be operated. This relay locks over a circuit from ground at its winding through its make contact and armature 603, conductor 601, to the upper break contact and armature 303 of relay REL, Fig. 3, to grounded battery. The arrangement of relays and armatures in the 2nd digit identification storage relay group, and also in the fix group, is the same as that in the 1st digit identification group shown, except that there is no blank lead BL in cable 607 connected to the armatures of the fix relay groups.

The brushes of distributor DR1, as they advance, next contact segment 2 of ring 11, and the brush b6 completes a circuit from grounded battery on segment 2 of ring 12, through the brush and segment 2 of ring 11 to conductor 6 in cable 402, and thence to the tape stepping magnet TS and the print magnet PM, Fig. 1, thereby printing the character on the monitor printer and also stepping the tape in tape transmitter TTR1. As the distributor DR1 rotates, the brushes thereof close circuits to segments 4 of rings 1, 3, 5, 7 and 9 connecting the 2nd digit identification relays, shown in Fig. 6, to the tongues of the tape transmitter TTR1, Fig. 1, in a manner similar to that of the preceding character, thereby actuating the relays in the second digit identification group in accordance with the code for the digit 4.

Similarly, as the tape is advanced, in transmitter TTR1, the remaining characters are printed by the monitor printer, and are transmitted by segments 5, 8, 10 and 12 of rings 1, 3, 5, 7 and 9 of DR1 and stored in the Fix relay group, and the Range and Data (Tens) relay groups R₁ to R₅, DT1 to DT5, and corresponding relays in the Data (Units) group shown in Fig. 6.

When the brush b6 of distributor DR1 reaches segment 12 of ring 11, this completes a circuit from grounded battery on segment 2 of ring 12, through the brush, segment 12, conductor 6 in cable 140, to the tape step magnet TS of the tape transmitter TTR1 of Fig. 1, and at the same time energizes the print magnet PM in the monitor printer, recording the last received character of the data. Stepping of the tape transmitter advances the next character under the sensing pins which is "space" in this example.

When the brush b6 of distributor DR1 reaches segment 14 of segmented ring 11, ground is applied from segment 4 of ring 12 through the brush, segment 14, conductor 9 in cables 401 and 133, and conductor 9 out of cable 133, Fig. 3, to the start magnet SM2 of distributor DR2, and thence to grounded battery, actuating the start magnet and releasing the brush b of the distributor for rotation. As the distributor DR2 leaves its rest position, the circuit through segment 1 of ring 1 is opened, thereby deenergizing start magnet SM1 of distributor DR1, Fig. 4. Distributor DR1 then comes to rest with its brushes on its stop segment 1. Distributor DR1 waits until distributor DR2 has completed its cycle of transmission hereinafter described, before continuing to take the remainder of the message from tape transmitter TTR1.

Selection of gang relays in the record board

Each horizontal row of the record board contains storage or recording units NPT, NPU, F, IT, IU, TT, TU, AT, AU, the upper row 14 of which is shown in Figs. 3, 6 and 9. Preferably, although not necessarily, these are recording indicators of the type disclosed in Haselton et al. Patent No. 2,155,825, issued April 25, 1939. Such indicators are provided with a set of equally spaced contacts corresponding in number to the number of positions to which the indicator drums may be moved, the contacts being arranged in a continuous series. The wiper arm is attached to the indicator drum assembly and engages the contacts of the indicator in accordance with the instant setting of the drum; for example, if the drum is set to display the digit 1, the wiper will be in engagement with contact 1; similarly, if the indicator is set to its blank position, the associated wiper will be in engagement with its blank contact BL. The wiper contact assemblies herein referred to are illustrated schematically in arcuate form in the drawings to show more clearly the electrical circuits connected thereto. It will be understood, however, that these wipers take settings in accordance with the flight identification and information digits or symbols posted by the indicators. As each of the indicators reaches its blank or home position, during the transmission to the indicator of restoration pulses in a manner hereinafter described, the restoration circuit to ground is opened and an actuation or resetting circuit is closed, by a switch element, such as *s* in the indicators of Fig. 9, thereby to cause the indicator to stop when it reaches its home position and its coil switched to an actuation circuit, as disclosed in the patents to Haselton 2,049,499, issued August 4, 1936, and Hicks et al. 2,189,581, issued February 6, 1940. The subsequent application of the resetting or actuation impulses to the indicator causes the switch member *s* to be restored to its former position when the indicator leaves its blank position during the resetting operation. Fifteen of such rows of indicators are indicated in the drawings, the bottom row 00 being shown in the upper portions of Figs. 4 and 7 and the lower portion of Fig. 9, and the intermediate rows 01 to 13 being indicated diagrammatically in Figs. 3, 6 and 9. It will be understood that in practice a great many more rows than those indicated will be employed in the record board; in an average size installation there may be approximately 2500 rows of such indicators. The indicators F, IT and IU in each row, Figs. 6 and 7, have initially been set in a manner disclosed hereinafter to positions corresponding to the flight number to be recorded in that row; the settings of these indicators determine whether or not the information stored in the Fix and Identification relay storage groups shown in Fig. 6 will operate the gang relay associated with that row in the record board, such as relay GA14 of Fig. 3. As soon as the Fix and Identification digits have been recorded, selection circuits are set up in the pyramidal arrangement of contacts on the storage relays as shown for the 1st digit Identification, Fig. 6. These circuits are multiplied to the corresponding indicator units in each of the rows of the record board; for example, the circuits from the 1st digit Identification storage relays are multiplied through a cable 605 to the bank of contacts of the IT indicators in each of the horizontal rows 00 to 14. Similarly, the circuits from the 2nd digit Identification storage group are multiplied

through cable 606 to the contact bank of the IU indicator in each horizontal row, and the circuits of the fix storage relays are multiplied through cable 607 to the contact bank of the F indicator in each horizontal row.

In the example cited, the flight to be posted was designated No. 34 in Fig. 1, and relay 111 of the 1st digit identification group is operated and the remaining ones of the group are unoperated. Therefore, conductor 3 of cable 605 will have ground at operated armature 694 of relay 111 applied thereto, and in those rows where the IT indicator is resting on terminal 3, as in Fig. 6, a circuit will be completed to operate the associated ITC relay in that row. Let us assume that row 14 has been assigned to flight 34, Fix 1. In other rows where the IT indicator also is resting on terminal 3, the ITC relay will also operate, but since the selection of a given row depends upon an exact match in all three indicator positions IT, IU and F, a complete circuit can only be established in the row assigned to that flight. Continuing with our example, the 2nd digit identification storage relays of Fig. 6 will apply ground to conductor 4 in cable 606, and since the wiper of the indicator IU in row 14 is resting on terminal 4, the relay IUC14 will operate. Similarly, the Fix storage relays will energize lead 1 in cable 607 and since the wiper of the F indicator in row 14 is resting on this position, the FC14 relay will be operated. The combination of operated relays ITC14, IUC14 and FC14 completes a series circuit from ground through make contact and armature 610 of relay IUC14, make contact and armature 611 of relay ITC14, conductor 612, make contact and armature 613 of relay FC14, conductor 614, winding of gang relay GA14, Fig. 3, to grounded battery, operating relay GA14. The relay GA14 is maintained energized through the circuit previously described, so long as the permutation relays in the 1st digit Ident, 2nd digit Ident, and Fix storage groups remain operated, and these latter relays are held operated until the brush *b* of distributor DR2 has reached segment 45 of the distributor ring 1, and the release relay REL has operated to remove battery, at its armature and break contact 303, from the holding circuit 601 for the storage relays of Fig. 6.

The operation of relay GA14 connects by means of cable 338, the coils of the recording indicator units NPT, NPU, F, IT, IU, TT, TU, AT and AU of row 14 through the pulsing cable 305 to the groups of range relays NP, F, I, T, A, and also to the group of pulsing relays P1, P2, P4 and P1 and AG of Fig. 3. The operation of relay GA14 also connects ground at 336 over conductors 4 to 11 in cable 338 to contacts on the "present position" PPT and PPU relays of row 14, Fig. 6. The purpose of these relays is to control the selection of the particular row of indicators in the display board where flight 34, Fix 1, is at present displayed. The present position tens PPT and units PPU relays, eight in number, are of the mechanical-latching, electrical-reset type, and store in four unit permutation code a two-digit number corresponding to the row number in the display board where flight 34, Fix 1, is posted.

Fig. 12 shows the details of one form of mechanical-latching type of relay, which may be employed. The operating winding *a* of the relay is connected, in multiple with the other relay windings *b*, through a conductor 651 to a source of grounded battery 649. All the reset windings *R* are connected in series, by means of a conductor 650, to the source of battery 649. When the

operating winding 0 of any of the relays is energized, it attracts its armature *a* and closes a circuit through its make contact, for example, from conductor 4 in cable 338 to conductor 1 in cable 616. As the armature *a* moves towards its make contact, it lifts a pivotally-mounted mechanical latch *b* which drops down behind the armature *a* and keeps it locked in circuit-closing position until the release or reset winding *R* is energized. Energization of the reset winding attracts its armature and raises the latch *b*, whereby the armature *a* returns to its open position, either under the influence of a spring or by gravity.

The ground circuit from 339, Fig. 3, is applied selectively through the closed contacts of those relays PPT, Fig. 6, which are operated, and through certain of the conductors 1, 2, 3 and 4 of cable 616 to the windings of relays PT1, PT2, PT3 and PT4, Fig. 7. Similarly, the contacts of those relays PPU which are operated, extend ground over certain of the conductors 5, 6, 7 and 8, cable 616, to the windings of relays PU1, PU2, PU3, PU4, Fig. 7. The relays PU and PT operate in combination in accordance with the permutation codes stored on relays PPU and PPT and serve to select one of ten cable leads 9 to 9 through the conventional pyramidal arrangement of armatures and contacts associated with the relays PU and PT.

Let it be assumed that flight 34, Fix 1, appears in the bottom row 00 of the display board shown in Fig. 5. Consequently, the permutation codes for 00 will be recorded on the present position storage relays PPT and PPU of row 14, Fig. 6, of the record board. This combination of circuits will have operated relays PT1, PT2, PT4, PU1, PU2 and PU4, Fig. 7, so that the 0 lead in each pyramid of these relays will have ground applied thereto from the apex 716 or 717. Ground will be fed from apex 717 through the operated inner armatures and make contacts of relays PT1, PT2 and PT4 and the unoperated inner armature and break contact of relay PT3, through conductor 0 to operate relay PT00, Fig. 7, and the 0 contact of each of the relays PT00 to PT00 will have ground applied thereto from the apex 716, through the multiple cable 718. Since relay PT00 is the only one operated, however, the conductor 00 in cable 701 will be the only one having ground applied thereto. This will complete a circuit from grounded armature 716 of energized relay PU1 through operated inner armature and contact of relay PU2, non-operated inner armature and break contact of relay PU3, operated inner armature and make contact of relay PU4, lead 0 of cable 718, contact 703 of relay PT00, lead 00 of cable 701, to the winding of display board gang relay DGA00, Fig. 5, to grounded battery. The operation of relay DGA00 connects the coils of the display board indicators IT, IU, TT, TU, AT and AU to the pulsing multiple through cable 501 and cable 305, Figs. 3 and 4, to the range or selection relays NP, F, I, T, A, Fig. 3, and the pulsing relays P1, P2, P4, P7 and AG. The display board indicators need not be of the recording kind employed in the record board, and may be of any suitable display type such as disclosed in the aforesaid Patents Nos. 2,049,499 and 2,189,581. The switch members *s* on the indicators open the restoration circuits to ground when the indicator drums reach their blank positions, the switch members being reclosed when the indicators are stepped from their blank positions during the resetting operations.

During the operation of distributor DR1 a com-

bination of range storage relays R1 to R5, Fig. 6, has been operated to apply ground either to lead 1 or lead 2 of cable 620. In the example cited the range selected (time) was No. 3, the permutation code for which energized relay R4 only, and consequently ground was applied through the contacts of relays R1 to R5, lead 2 of cable 620, to the winding of relay T, Fig. 3, and thence to grounded battery. Relay T operated and at its armatures and make contacts connected through the circuits from pulsing relays P1, P2, P4 and P7 to pulsing leads 14 and 15 in cable 305, which are extended, through contacts of relay GA14 and cable 338, to the windings of the time indicator units TT and TU, Fig. 9, of row 14 in the record board, and are also extended through conductors 3 and 4 in cable 501 and contacts of relay DGA00 to indicators TT and TU of row 00 in the display board, Fig. 5.

20 *Operation of distributor DR2 for pulsing the selected indicators*

In Fig. 5 a relay M is arranged to tie together the pulsing multiples of the various rows in the display board. As later described under Sequencing, it is necessary to utilize five separate pulsing multiples 501 to 505 in the display board. However, for the purpose of posting a single flight, these multiples must be tied to the range and pulsing relays NP to AG shown in Fig. 3. When relay M is operated, as described below, the corresponding leads of the pulsing multiples 501, 502, 503, 504, 505 are tied together by means of the multiple connections *m* on the contacts of relay M. The first operation accomplished by distributor DR2, Fig. 3, as its brush arm *b* leaves the rest position is to apply ground from ring 2 to segment 2 of ring 1, and thence over lead 2 of cables 301 and 133 to the winding of the M relay, Fig. 5, to grounded battery. Through its innermost make contact a locking path for relay M is maintained over lead 3 of cables 133 and 301, through the break contact and armature 308 to ground on relay REL, Fig. 3. The relay M remains locked up until the REL relay is operated from segment 45 of DR2 at the end of the cycle of the distributor. The brush *b* of distributor DR2 next closes a circuit to segment 3 of ring 1, but this circuit is utilized only when posting from the keyset shown in Fig. 2, which will be described later. The next circuit closed by distributor DR2 is to segment 4 of ring 1. It will be noted that the ten even numbered segments 4 to 22, inclusive, are connected together and furnish an operating path for the pulsing relay P7. Each time that relay P7 operates, battery through break contacts and armatures 310 and 311 of relay AG is fed through armatures 312 and 313 and associated make contacts of relay P7, make contacts and associated armatures 314 and 315 of relay T, to leads 14 and 15 in the pulsing multiple 305. The ten pulses generated in passing over segments 4 to 22 on ring 1 of distributor DR2 restore the selected indicators in the display board and record board to their blank positions, irrespective of what their former positions were. As each indicator reaches its blank position the restoration circuit to ground is automatically opened by the indicator switch member *s* or *s'*, thereby stopping the indicator in this position. When the brush arm of distributor DR2 reaches segment 24, ground from ring 2 is fed through the brush over conductor 318 to the winding of relay AG, and thence to grounded battery, causing relay AG to operate. The oper-

ation of AG removes the pulsing battery formerly supplied through break contacts and armatures 310 and 311 to the pulsing relays, and also supplies ground through its lower outer armature 319 and make contact over conductor 18 in cable 305, through contact 18 of relay GA14, Fig. 3, to the actuation ground feeder 320 for the indicators in row 14 of the record board. The ground over conductor 18 in cable 305 is also extended through lead 31 in cable 501, Fig. 4, through the outer right hand contact of relay DGA00, Fig. 5, and the winding of relay AG00 to grounded battery. Relay AG00 operates and connects ground through its contacts 1 to 6 to one end of the windings of the indicators IT to AU in row 00 of the display board. The indicators in the record and display boards are now in condition to move from their blank positions when actuation or resetting pulses are sent over the pulsing multiple.

As the brush arm *b* of distributor DR2 passes segment 26 of ring 1, the pulse relay P1 is operated once, and similarly when the brush arm passes segments 28 and 30, which are strapped together, the pulse relay P2 is operated twice. When the brush arm passes the seven even segments 32 to 44, inclusive, the pulse relay P1 is operated seven times, and when the brush arm passes the four odd-numbered segments 33 to 39, inclusive, the pulse relay P4 is operated four times. It will be seen that the combination of one, two, four and seven pulses forms an additive permutation code which enables any number of pulses from one to ten to be produced in accordance with the circuit set up by the Data (Tens) and Data (Units) storage relays DT1 to DT5, etc., in Fig. 6. The pyramidal arrangement of contacts of the Data (Tens) relays is such that the introduction of a five-unit permutation code into these relays energizes a combination of four leads in additive permutation code so that the additive code corresponds to the digit transmitted to the windings of the storage relays.

An alarm device such as the lamp 669 operates whenever the relays Data (Tens) or Data (Units) are set to positions representative of code signals other than the code signals for the digits 1 to 9 and 0, such as may result from the improper operation of the teleprinter keyboards or other transmitters by the sending operators, or from other causes, as failure of the line L, static conditions, and the like. When this indication of an improper signal is received, an attendant at the air traffic control center is thus immediately apprised of this condition, so that instructions may be issued to the sending operator by means of available communication facilities to the effect that his message has been incorrectly received and request that the message be repeated.

In the example chosen, the data consisted of tens digit 3 and units digit 5 representing the time 35. The permutation code for 3 is one marking, which caused relay DT1 to be operated. The circuit from battery on the armature 622 and its associated make contact of DT1, and armature 623 and break contact of relay DT4, armatures 624 and 625 and associated break contacts of relay DT2, armatures 626 and 627 and associated break contacts of DT3, break contacts and armatures 628 and 629 of relay DT5, energizes leads 1 and 2 in cable 630, which in turn supply battery to inner armature 325 of pulse relay P1 and armature 326 of pulse relay P2, Fig. 3. Thus, the passage of the brush arm over segments 26,

28 and 30 will generate a total of three pulses which will be conducted through the range relay T to lead 14 of the pulsing multiple 305. Similarly, the data or digit 5 stored in the Data (Units) relays will energize leads 8 and 6 in cable 630, Fig. 6, which will supply pulsing battery to armatures 330 of pulse relay P4 and 331 of relay P1. When the brush passes over segments 26, 33, 35, 37 and 39, five pulses will be generated, which will be fed through the inner make contact and armature 315 of the T relay to lead 15 in the pulsing multiple 305, and lead 4 in cable 501. Thus, the indicators TT and TU, Fig. 9, in row 14 of the record board and the indicators TT and TU in row 00 of the display board will have been pulsed to display the data 35, representing the time of passing of flight 34 over Fix 1.

When the brush arm of distributor DR2 reaches segment 45, a circuit is closed from ground to the winding of the REL relay, Fig. 3, which operates and releases, at armature 308, the AG relay, Fig. 3, and the M relay, Fig. 5, while the circuit opened at armature 303 and associated break contact of relay REL releases the previously locked up data storage relays shown in Fig. 6. Continuation of the brush arm *b* to the rest position recloses the circuit through segment 1 of the start magnet SM1 of distributor DR1, so that the next portion of the incoming message may be stored in the storage indicators. Relay REL at its armature 330 and associated break contact opens the locking path over conductor 141 and contact 7 of relay TC, Fig. 1, to the lower locking winding of relay TC. This relay does not release, however, since it is still held operated through its upper winding by the circuit from point 7, bank C, of the seeker switch SS.

During the previously described revolution of the brush arm *b* of distributor DR2, circuits were closed at segments 7 and 15 on ring 1 to operate the PTR relay, Fig. 3. The function of the PTR relay is to step out the two "space" characters recorded in the perforated tape between the first portion of the message and the second portion thereof, generally in the manner explained in the Marshall et al. patent. The first operation of the PTR relay closed a circuit from battery at the armature of the PTR relay, Fig. 3, over conductor 6 of cable 140 to the print magnet PM of the monitor printer and the tape step magnet TS of the tape transmitter TTR1, both of which are shown on Fig. 1. This operation recorded the first space character on the monitor printer and simultaneously advanced the tape to bring the second space character under the sensing pins of the tape transmitter. This selectively energized the magnets in the monitor printer to set up the second space character. When the brush arm *b* passed segment 15, the second operation of the PTR relay energized the print magnet PM and the tape step magnet TS, thereby recording the second space character on the monitor printer and advancing the tape in the tape transmitter to bring the first character of the second portion of the incoming message under the sensing pins.

The distributor DR1 is now in position to accept and store the second portion of the message which comprises the Identification characters 3, 4, Fix 1, Range 2 (altitude) and data 45 representing the altitude in hundreds of feet, followed by the end-of-message signal. Over the circuit previously described, the start magnet SM1 of distributor DR1 is energized and the brush arm makes a cycle of the segments of the

distributor, thereby storing the Identification, Fix, Range and Data characters of the second portion of the message in the storage relays shown on Fig. 6.

As the brush *b6* of distributor DR1, Fig. 4, passed segment 12 of ring 11, a circuit was closed from battery on segment 2 of ring 12, through segment 12, over conductor 6 in cable 140, to the print magnet PM of the monitor printer and the tape step magnet TS of the tape transmitter. This operation printed the last character (5) of data on the monitor printer and at the same time advanced the perforated tape to bring the end-of-message character under the sensing pins of the tape transmitter. When this occurred, circuits were closed over leads 1, 2, 3, 4, 5 in cable 150 to the windings of the RS1 to RS4 relays of the group A in Fig. 1. The combination of operating paths representing the code for the end-of-message signal caused relays 2 and 4 to be operated, thereby closing a circuit from battery at RS1 to the upper end of the winding of relay RS5. Relay RS5 does not operate, however, until the other end of its winding is connected to ground through conductor 8 of cable 133 and segment 5 of the distributor DR2, which occurs during the pulsing of the indicators. When brush *b6* of distributor DR1 reaches segment 14 of ring 11, ground from segment 4 of ring 12 is supplied over conductor 9, cables 401 and 133, to energize the start magnet SM2 of distributor DR2, Fig. 3. As previously described, the circuits set up by the first and second digit identification storage relays, the fix relays and the range relays coact to select gang relay GA14, Fig. 3, and gang relay DGA00, Fig. 5. In this case the range code for the character 2 causes lead 1 in cable 620 to be energized to operate the range relay A (altitude) shown in Fig. 3. The pulses generated during the revolution of distributor DR2 and controlled by the circuits set up in the Data (Tens) and Data (Units) relays are now sent out over conductors 16 and 17 of cable 305 to operate the indicators AT and AU of row 14 in the record board and similarly indicators AT and AU in row 00 of the display board. This operation posts the altitude 45 (4500 feet) in these indicator positions on both boards.

During the revolution of distributor DR2, a circuit was closed as the brush *b* passed over segment 5, from ground on ring 2 through the brush and segment 5, over conductor 8 of cable 133 to the lower end of the windings of relays RS5 shown in Fig. 1. Since the upper end of the winding of the RS5 relay shown in Group A previously had battery connected thereto upon the reception of the end-of-message signal, relay RS5 now operates and removes ground, at its armature and break contact 122, from conductor 121. In the meantime the stepping ahead of the perforated tape through the tape transmitter TTR has opened the ground circuit at contact 125 of the auto-control switch AC because the slack tape loop has been depleted. The removal of ground from conductor 124 as well as from conductor 121 releases the relay L. Relay L upon releasing opens at its armature 129 and associated make contact the operating circuit of relay TC and the start magnet SM1 of distributor DR1. Relay TC does not release immediately since it is locked up through its own contact 1 to ground over conductor 141 supplied through armature 330 of the REL relay, Fig. 3. When the distributor DR2 completes its revolution, relay REL is operated as previously described, and at its operated armature 330 and break contact releases the relay TC.

The release of relay L removes the ground from the hunting circuit of the rotary switch magnet SSM, Fig. 1, so that unless another incoming message is waiting, the switch SS will remain at its previous position.

Operation of keyset

Prior to the reception and posting of the incoming message hereinbefore referred to, the operator had operated the keyset shown in Fig. 2 in order to display in predetermined positions on the record board and display board at least the identification numbers relative to the various flights concerning which information is to be transmitted, each flight being assigned to the particular section of the display board containing the flight data relating to a particular Fix. On the record board the locations may be chosen at random, but the Fix to which the flight is assigned is recorded on a Fix storage indicator such as F in horizontal row 14 in Fig. 6 or row 00 in Fig. 7. In initially setting up these indicators it is not necessary for any data, such as time and altitude, to be inserted, although it is frequently done in accordance with proposed flight plans, and upon the reception of incoming signals relating thereto the actual data is posted instead of the estimated data.

Since the rows 00 to 14 in the record board are assigned at random, each row is provided with a group of "present position" storage relays designated PPT and PPU, Figs. 6 and 7, which have recorded upon them the horizontal row number occupied by the same flight in the display board. Each horizontal row in the record board is also provided with a Fix indicator F, as above stated, upon which is stored the Fix in which the flight is displayed on the display board. Each horizontal row in the record board is also provided with two recording "new position" indicator units such as NPT and NPU, Figs. 3 and 4, which record the new horizontal position in the display board to be occupied by the flight data posted in that row of the record board.

Referring to the keyset of Fig. 2, it will be seen that there are seven rows of push buttons which are of the mechanical locking type, as indicated by the slideable locking bar 200 which extends to all of the keys SEQ to A in the row. When any key of the row is depressed, the tapered or conical edge of the body portion of the key shifts the bar to the right, and passes through an aperture in the bar and the key is held depressed by the bar until the key release magnet KR is energized, which moves the locking bar to the left and releases the key. One locking bar is provided for each row of keys, and each bar is released by magnet KR. The left hand row of seven push buttons is used to select the type of operation to be performed by the keyset. The next two rows designated PP Tens and PP Units are used to set up present positions by operating various combinations of the PPT and PPU relays, Figs. 6 and 7, in permutation code. The next two rows designated Data Tens and Data Units are used to control the number of impulses sent to any of the indicator units selected by means of the range keys NP, F, I, T and A in the left hand row. The last two rows, designated Hor. Pos. Tens (horizontal position tens) and Hor. Pos. Units (horizontal position units), are used to select the row in the record board where a flight is to be initially posted. When information regarding a proposed flight is received by the operator,

the flight number is posted in a selected row in the record board and display board.

Prior to receiving the preceding message regarding flight 34 over the line from teleprinter 101, Fig. 1, the local operator will have posted the flight number 34 and the Fix 1 on the record and display boards by the use of the keyset. The operator will have also selected a row in the display board where this flight may initially be displayed in proper relation to other flights on the display board. The operation of posting flight 34, Fix 1, in row 14 of the record board and row 00 of the display board will now be described. Since the information to be posted comprises the flight number 34, the present position 00, and the Fix 1, two keyset operations will be required. The first operation will be the posting of the flight number 34 in the Identification, Range and the storage of the present position 00 in the PPT and PPU relays in the selected row 14 of the record board. The operator depresses the 0 keys in the PP Tens and PP units rows. Key 3 in the Data Tens row and key 4 in the Data Units row are operated, and in order to select row 14 of the record board which happened to be idle at the time, the operator also depresses key 1 in the horizontal position tens row and key 4 in the horizontal position units row.

The last operation is that of selecting the range, which is performed by depressing the I key in the left hand row of the keyset. The left hand contacts of the I key close a circuit from ground at 201 through the closed contacts of the key, and over conductor 202 to the winding of the K relay, Fig. 1, and thence to grounded battery. As previously described for the operation of the L relay, the K relay applies ground through its operated armature 126 and the upper armatures on relays L, R1 and R2 to all contacts of bank A of the selector switch SS except terminals 4 and 8 which were disconnected at armature 126 and associated break contact of relay K. The application of ground causes the selector switch magnet SSM to be energized and step the switch through its self-interrupting armature 128 until it comes to rest on either terminal 4 or 8, whichever was reached first. The operation of relay K, also closes a path to operate relay KS, Fig. 2, from battery on armature 152 of relay K and associated make-contact, conductor 153, winding of the KS relay, conductor 204, terminal 4 of bank C of switch SS, wiper of bank C, conductor 154, terminal 4 of bank B of switch SS, wiper of bank B, conductor 4 in cable 133, conductor 4 in cable 401, Fig. 4, break contact and armature 700 of relay SST, Fig. 7, conductor 1 in cables 401 and 133, segment 1 of ring 1 of distributor DR2, Fig. 3, and thence through brush b to the grounded feeder ring 2 of the distributor, thereby operating relay KS, Fig. 2, and closing through the various groups of contacts controlled by the armature 204 of that relay.

The closure of the contacts connected to the horizontal position tens and horizontal position units keys, selected and operated gang relay GA14 over the path to be described. Ground through the contact of key 1 in horizontal position tens row operates a corresponding tens relay HPT10, Fig. 2. Ground through the contacts of horizontal position units key 4 applied ground to the No. 4 contacts on all HPT relays, but HPT10 being the only relay operated, the final path is over lead 14 in cable 208, conductor 614, Fig. 3, to the winding of gang relay GA14 and thence to grounded battery, operating GA14. The opera-

tion of the KS relay, Fig. 2, also closed a circuit from ground 201 through the normally closed contacts of the SEQ push button, over conductor 209 to the winding of start magnet SM2 and thence to grounded battery, operating the start magnet and releasing the brush arm b of DR2. As previously described, the first operation produced by the distributor is the operation of relay M, Fig. 5, when the brush b passes over segment 2. This ties together the various multiples 501 to 505 of the display board. When the brush b connects ground to segment 3 of ring 1 of the distributor, the path is completed over lead 334 through any operated PP tens or PP unit keys, Fig. 2, which in this case are the 0 keys in each row, over conductor 210, contact of KS relay, conductor 19 in cable 305, contact of operated relay GA14, conductor 1 in cable 617 to the reset coils R of the PPT and PPU relays which are connected in series by conductor 650, and thence to grounded battery 649. The operation of the reset coils R of these relays releases the armatures of those which were previously set.

The right hand contacts of the PP tens key 0, Fig. 2, have closed circuits from ground at 212 to conductors 214, 215 and 216 which continue through conductors 20, 21 and 23 of cable 305, and conductors 2, 3 and 5 of cable 617, to the operate windings of relays PPT1, PPT2 and PPT4, Fig. 6. This combination represents the permutation code for the digit 0. Similarly, the left hand contacts of the PP units key 0 closed circuits from ground 218 to conductors 220, 221 and 222, contacts of KS relay, and conductors 24, 25 and 27 of cable 305, contacts of relay GA14, conductors 6, 7 and 9 of cable 617, to the operating windings 0 of relays PPU1, PPU2 and PPU4, Fig. 6, thereby registering the permutation code for the digit 0 in the PPU relays.

When the contacts of the PPT and PPU relays are closed, a circuit is closed from ground at 336, Fig. 3, through contacts of the relay GA14, over conductors 4 to 11 of cable 338 to the contacts of the PPT and PPU relays, and thence through the contacts of the operated ones of these relays over conductors 1, 2, 4, 5, 6 and 8 of cable 616 to the windings of relays PT1, PT2, and PT4, PU1, PU2 and PU4, Fig. 7, to battery.

The combination set up by the operated PT1, PT2 and PT4 relays, through the pyramidal armature arrangement shown, energizes conductor 9 which connects to the winding of the PT 00 relay. The operation of this relay completes a circuit from the previously energized 0 lead of the PU relay group to lead 00 in cable 701. This path completes the operating circuit for relay DGA 00, Fig. 5. The operation of relay DGA 00 connects the group of indicator units in the 00 row of the display board to the pulsing multiple.

The operation of the I push button in the left hand row of keys shown in Fig. 2 has closed a circuit from ground at 201 through the right hand contacts of the push button I, over conductor 3 of cable 225 to the winding of the I range relay, Fig. 3. This relay connects the pulsing leads from the relays P1, P2, P4, and P7 to the pulsing multiple conductors 12 and 13 in cable 305 where they eventually terminate on the coils of the IT and IU indicators in the record board horizontal row 14, and the IT and IU indicators in row 00 of the display board.

As the brush b of the distributor DR2 continues its rotation, circuits closed through the even numbered segments 4 to 22, inclusive, cause

the relay P1, Fig. 3, to generate ten restoration pulses for resetting the IT and IU indicators to their blank positions.

The operation of the Data Tens push button 3, Fig. 2, applies battery 226 through the contacts of key 3 to leads 1 and 2 of cable 227, and thence to armature 325 of the P1 relay and armature 326 of the P2 relay, Fig. 3. The operation of the push button 4 in the Data Units key strip connects battery 230 to conductor 6 in cable 227, and thence to armature 330 of the P4 relay. As the distributor brush arm completes its cycle, the AG relay will have been operated from segment 24 as previously described, and the P1 relay will be operated once, the P2 relay twice, and the P4 relay four times, thereby transmitting three pulses to the pulsing multiple lead 12 in cable 305 and four pulses to the pulsing multiple lead 13 in cable 305. In this way the flight identification 34 is posted in the appropriate positions in horizontal row 14 of the record board and row 00 of the display board.

When the brush *b* reaches segment 45 on ring 1 of distributor DR2, the release relay REL is operated, and at its armature 330 and make contact 301 establishes a circuit from ground through conductors 340 and 341 and the operated contacts of relay KS, Fig. 2, to the key release magnet KR and thence to grounded battery. The actuation of the key release magnet actuates the various locking bars 200, which have held the depressed keys in their operated positions, to release the keys which return to their normal positions shown in Fig. 2. The release of the I push button in the left hand row opens the circuit from ground 201 over conductor 202 which held the K relay, Fig. 1, operated. When the K relay releases, battery is disconnected at its armature 152 and this releases the KS relay, thereby disconnecting the keyset from the remainder of the circuit.

In a similar manner the operator posts the Fix number 1 on the F indicator, Fig. 6, in row 14 of the record board. Since there is no F indicator in the display board, the record of the Fix is only retained in the record board. At some later time the operator will post, by means of the keyset, the new position indicators NPT and NPU of row 14. These indicators record the position in the display board where the flight data of row 14 is to be posted when the automatic sequencing operation takes place. The setting of the New Position units depends not only upon the data in row 14, but also upon changes in the flight data in other rows. Generally the new position numbers are assigned and changed to maintain a chronological sequence of flight arrival times at any particular Fix, although the new position numbers may be assigned to produce any useful and convenient arrangement of the data on the display board.

With the Identification and Fix indicators and the Present Position relays carrying appropriate information, the record board is capable of receiving further information on flight 34 as it is received automatically over the incoming circuits L1, L2 or L3.

If it were desired to initially post, by means of the keyset, a proposed flight plan in regard to any particular flight, the proposed time and altitude of the flight at any particular Fix may be set up in the proper row of indicators in the record board, under the manual control of the operator who depresses in succession the data tens, units, horizontal position tens and horizon-

tal position units keys, and then the range key corresponding to the position in which the additional information is to be posted. The manner in which the selected indicators are pulsed to the desired positions is generally as heretofore described, it being understood that the appropriate one of the range relays NP, F, I, T and A in Fig. 3 are energized by depression of the associated key in the left hand bank of keys. If at any time it becomes desirable to wipe out the data in any posted row of indicators in the record board, this is accomplished by depression of the wipeout key WO following the selection of the appropriate horizontal position keys, and in this case all of the range relays NP to A in Fig. 3 are operated at the same time, after which ten restoration pulses are transmitted to each of the indicators in the selected row.

Multiple row sequencing operation

As hereinbefore stated, the control personnel may desire the flights to be displayed on the display board of Fig. 5 in chronological order in each Fix group, usually in order of time, although the desired sequence may be in accordance with the altitude data or in any other order in which it is desired to have the flights displayed. To establish the desired sequence of the items posted on the display board, the keyset operator notes, for example, changes in the time posted on the record board in regard to the various flights, and resets the "new position" storage indicators NPT and NPU of Fig. 3 to assign new position numbers in accordance with the desired chronological sequence. The indicator settings also take into account the division of the board into Fixes, so that the new positions of the flights in any particular Fix are in chronological sequence. At intervals determined by the control personnel, the flights are automatically rewritten on the display board to appear under the proper Fix and in the order dictated by the settings of the new position indicators. In the sequencing operation any desired number of horizontal rows of indicators may simultaneously or concurrently be rewritten on the display board, for example, ten, fifteen or twenty rows at a time, thereby to minimize any inconvenience caused by changing the settings of the indicators in the display board, and also to minimize any time lost in setting up new incoming information in regard to any of the flights posted on the display board. For convenience in describing the sequencing operations, it will be assumed that five rows of indicators are to be reset at the same time, for example, rows 00 to 04, 05 to 09, or 10 to 14.

Sequencing is initiated from the keyset by operating the SEQ button, Fig. 2. Upon securing access to the equipment through the seeker switch SS of Fig. 1 in the manner hereinbefore described with reference to keyset operation, the KS relay of Fig. 2 is operated. When the button SEQ is depressed, the circuit through its inner left hand break contact and spring is opened, removing ground from conductor 209 and thereby preventing energization of the start magnet SM2 of distributor DR2 at this time. Since the SEQ push button is mechanically locked in depressed position by the latch 200, the sequence start relay SST, Fig. 7, remains operated from battery at the upper end of its winding, through the winding and conductor 5 in cables 431 and 133, conductor 5 out of cable 133 in Fig. 2, contacts of relay KS, conductor 240, and operated right hand contacts of button SEQ to ground 201,

until the key release magnet KR subsequently is energized to release the SEQ button. Relay SST, through its upper inner grounded armature and make contact 702, and conductor 704, energizes the start magnet SM3 of distributor DR3, Fig. 8, and starts the distributor in operation. Segmented rings 1 and 2 of distributor DR3 control the selection of the fifteen ground supply relays GS00 to GS14, Figs. 6 and 7, in the record board in the following manner: Through 10 the rotary sequence collection switch SCS of Fig. 4 and the contacts of relay RP, the GS relays are selected in the order predetermined by the settings of the "new position" indicators NPT and NPU.

In order to explain the various sequencing operations, a specific example will be given. Let us assume that the flight information presently recorded in row 14 of the record board is to be transferred to the indicators in the bottom row 20 00 of the display board of Fig. 5, and that the information presently recorded in the indicators in row 00 of the record board is to be transferred to row 04 of the display board. To initiate this, the new position storage indicators NPT and NPU of row 14, Fig. 3, are set to the 00 position, as indicated by the settings 0, 0 of their wiper arms, and the new position indicators NPT and NPU of row 00, Fig. 4, are set to the 04 position, as indicated by the settings 0, 4, respectively, of their wiper arms. The flight which is recorded in row 14 of the record board, and whose new position indicators NPT and NPU are set to the 00 position, will have its GS relay (GS14) operated first. The circuit for operating this relay may be traced as follows: The first segment 0 of ring 2 of distributor DR3, Fig. 8, closes a circuit from grounded segment 802, through brush B1, conductor 0 in cable 705, armature 497 and break contact of relay RP, Fig. 4, to the 0 lead of the NPU (new position units) multiple cable 405, Figs. 3 and 4, bank terminal 0 of the storage indicator unit NPU of row 14, Fig. 3, rotary wiper arm of NPU, winding of the new position comparator relay NPC 14 to grounded battery. The operation of relay NPC 14 prepares a path at its armature and make contact 350 for completion of the operating path of the ground supply GS14 relay, Fig. 6. The operating path may be traced from ground on the rotary brush or wiper of bank A of rotary sequence collection switch SCS, Fig. 4, over conductor 0 in cable 406, bank terminal 0 and wiper of NPT storage indicator unit in row 14, Fig. 3, through armature and contact 350 of the relay NPC 14, conductor 351, to the winding of relay GS14, and thence to grounded battery, Fig. 6, operating the latter relay. The operation of this relay connects ground through its contacts 635, 636, Fig. 6, and 902 to 905, Fig. 9, to the wipers of recording units IT, IU, TT, TU, AT and AU.

In the example previously given, the information posted in row 14 of the record board consisted of flight identification No. 34, time 35 and altitude 45. Therefore, the wipers of the recording units IT to AU in row 14 are set as shown in Figs. 6 and 9 of the drawings. The ground applied through contact 635 of relay GS14 energizes lead 3 in cable 605, Fig. 6, which is connected to the winding of relay IT3 of the translator group C of relays of Fig. 7. The purpose of the Group C of code translator relays and similar groups D to H shown in Figs. 7 and 9 is to convert the ten-unit code in which the flight information is recorded into a four-unit permutation code for

storage on the relays shown in Fig. 10. It will be seen that certain of the leads 1, 2, 4 and 7 of cable 605, Fig. 7, which are translated into single permutation code elements, pass directly through the translator group, while other leads 3, 5, 6, 8, 9, 0 operate relays similarly designated whose function is to energize a combination of leads in permutation code. The operation of relay IT3 connected ground 719 through make contacts and armatures 711 and 712 to conductors 1 and 2 of cable 714, through contacts 1 and 2 of energized relay SMRO, Fig. 8, conductors 1 and 2 of cable 804, to the windings of storage relays ITS1 and ITS2, Group O, Fig. 10, and thence to grounded battery. These relays operate and lock through their inner make contacts, over conductor 1005 to ground through break contact and armature 715 of the SRL relay, Fig. 7. Relay SMRO had previously been operated by the passage of brush b1 of distributor DR3 over segment 0 of ring 2, the path being from ground on segment 802, brush b1, segment 0, conductor 0 in cable 705, to the winding of relay SMRO and thence to grounded battery, the relay having been energized in multiple with relay GS14 of Fig. 6.

Similarly, the information stored on recording units IU, TT, TU, AT and AU in row 14, Figs. 6 and 9, is translated by like translator groups D, E, F, G, and H, Figs. 7 and 9, and stored on relays 30 IUS4, TTS1 and TTS2, TUS1 and TUS4, ATS4, AUS1 and AUS4, all within group O in Fig. 10.

While the information recorded in row 14 was being stored in the relays of group O, Fig. 10, another circuit was completed by the distributor DR3, Fig. 8, from ground on segment 806 of ring 3 to segment 0 of ring 4, over conductor 807, conductor 1 in cable 412, Fig. 7, contact 1 of relay GS14, Fig. 6, conductor 1 in cable 640 to the reset windings R of all the relays 35 PPT and PPU connected in series by conductor 650, and thence to grounded battery 649. The operation of the reset coils erased any previous "present position" data recorded on these relays. However, a circuit had been set up to transfer the 40 new position number recorded on the NPT and NPU indicators to the PPT and PPU relays, which circuit may be traced from ground on brush wiper A of sequence collection switch SCS, Fig. 4, over conductor 0 in cable 406, to the winding of the 45 PPTO relay, Fig. 4. The operation of this relay connected ground 410 through its make contacts and armatures to conductors 2, 3 and 5 of cable 412, contacts on the GS14 relay, Fig. 6, conductors 2, 3 and 5 in cable 640, to the operate 50 windings O of relays PPT1, PPT2 and PPT4, and thence through conductor 651 to grounded battery 649. It will be noted that the duration of the 55 reset pulse was much shorter than that of the operate pulse, and consequently the new present position tens digit remained locked up when the 60 reset coils were deenergized as brush b2 of distributor DR3 left segment 0 of ring 4.

At the time that the new position tens was 65 transferred to the PPT relays, a similar operation was being carried out to transfer the new position units digit to the PPU relays. The circuit in this case is from grounded segment 802 of distributor DR3, Fig. 8, through brush b1, segment 0 of ring 2, conductor 0 of cable 705, armature 407 and associated break contact of relay RP, Fig. 4, conductor 0 of cable 405, to the winding of a 70 relay NPUO that is in the NP (units) code translating group in Fig. 4, which is like the adjacent 75 NP (tens) code group. The operation of the

NPUO relay grounds conductors 6, 7 and 9 in cable 412; these grounds extend through the conductors to contacts of relay GS14, Fig. 6, and thence through conductors 6, 7 and 9 of cable 640, to the operate windings 0 of present position units relays PPU6, PPU7 and PPU9 in row 14, and thence to grounded battery 649. As explained before, the reset coils R of the PPU relays have been energized in series with those of the PPT relays so that the former digit stored on the PPU relays was canceled, and the new position units number stored thereon.

The above description covers the transfer of the flight information stored in row 14 of the record board to the storage relays ITS1, etc., shown in group O on Fig. 10. The distributor DR3 now closes circuits through segments 1 of rings 2 and 4 to select that row in the record board bearing the new position number 01, Fig. 13, and a similar transfer of data to the group of storage relays shown in group 1 of Fig. 10 occurs. This process is continued until the information stored in the first five lowest-numbered rows of the record board, as determined by the new position numbers, has been transferred, through relays SMR1 to SMR4 and cables 814 to 817, to the groups of relays 0—4, shown in Fig. 10. It will be noted that row 00 in the record board bears the new position number 04 recorded on the NPT and NPU switch wipers, Fig. 4, and therefore the information stored in this row would have been transferred to group 4 of the relays on Fig. 10.

During the transferring operations the indicators in the rows 00 to 04 in the display board have been restored to their blank positions. This is accomplished by the selection of gang relays DGA00 to DGA04, Fig. 5, through the banks of the stepping switch DGS shown on Fig. 7. The operation of the sequence start relay SST, Fig. 7, connected ground from the armature 734 of the self-interrupting contact of the rotary switch operating magnet DGS, through the upper armature 735 and associated make contact of operated relay SST to the winding of the switch DGS for stepping the switch. This circuit is through the bank terminal 721 of bank A, which is strapped for homing the switch. The operation of DGS caused the six rotary wipers of the switch to advance immediately in the direction of the curved arrows to the second terminals on banks A, B, C, D, E and F. Grounds were applied over conductors 06, 01, 02, 03 and 04 in cable 722, which conductors terminate on the windings of relays DGA00 to DGA04 of Fig. 5. The operation of these gang relays connects the indicators in these rows of the display board to the pulsing multiples 501, 502, 503, 504 and 505, which are connected through cable 506 to the contacts of the pulsing relay P shown in Fig. 10. Battery for the contacts of the pulsing relay P is supplied through conductors 1 to 30 of cable 1010, and the armatures and break contacts of relay SAG to battery 1002.

The pulsing relay P is operated from segments 1 to 10 of ring 5 of distributor DR3, through brush b3 and solid segment 811 of ring 6, over conductor 812. The passage of the brush over these ten segments generates ten restoration pulses which simultaneously or concurrently restore the indicators in the first five rows of the display board to their blank positions. At the completion of restoration a circuit is closed by brush b1 of distributor DR3 to apply battery from segment 803 of ring 1 to segment 5 of ring 70 2, and thence over conductor 1 to the winding of

the relay SAG, Fig. 10, which operates and locks over its left hand inner armature and make contact to the break contact and armature 105 of relay SRL, Fig. 7. The operation of relay SAG removes the restoration battery 1002 from the contacts of the pulsing relay P. The operation of relay SAG also applies ground 1003 at its left hand outer armature and make contact to conductor 1012, which completes a circuit through the right hand outer contact of each of the DGA00 to 04 relays, Fig. 5, and thence to the windings of the actuating ground relays AG00 to 04, operating them. The operation of the AG00 to 04 relays applies ground to the right hand end 15 of the windings of indicators IT to AU in rows 00 to 04 of the display board. These indicators, whose switch contacts S' were opened when they reached their blank positions during restoration, are now in condition to receive actuation pulses 20 and be actuated to their new settings in accordance with the information stored in the relays of Fig. 10. The number of the resetting or actuation pulses is controlled through brushes b1 and b2 and segments 6, 7 and 8 of ring 2 and segment 6 of ring 4 of distributor DR3. These segments are of different lengths and respectively supply battery, from segments 803 and 808, for the duration of two pulses, one pulse and four or seven pulses to the contacts 1014 of the storage relays 30 of Fig. 10. It will be noted that the segment 6 of ring 2, for example, which is two pulses long, supplies battery over lead 2 to the contacts of all the storage relays ITS to AUS whose designations terminate in the numeral 2. This means that when any relays ITS2 to AUS2 in all groups of Fig. 10 are operated battery will be supplied to the contacts of the P relay for the duration of two pulses. Similarly, the other segments 7 and 8 of ring 2 and segment 6 of ring 4 supply the relays ITS1 to AUS1, ITS4 to AUS4 and ITS7 to AUS7, respectively. Segment 8 of ring 2 and segment 6 of ring 4 can supply battery simultaneously without interfering with the code, since four and seven pulses never are required together in any additive code up to ten.

As distributor brush b3 of DR3 passes over segments 11 to 20 of ring 5, ten more pulses are delivered through segment 811 and conductor 812 to the winding of the P relay. Dependent upon which combinations of storage relays that supply each particular contact of the P relay are operated, a group of pulses from one to ten in number will be sent over the leads of the pulsing multiple cable 506. In order to understand this operation more clearly, the specific example of the first digit 3 of the identification stored in group 0 of Fig. 10 will be considered. The relays ITS1 and ITS2 will be operated in this group. Consequently, battery from segment 6 of ring 2 will be supplied over conductor 2 to the contact 1014 of relay ITS2 and thence through conductor 1 of cable 1010 to contact 1 of the pulsing relay P. Consequently, as brush b3 passes over segments 11 and 12 of ring 4, two pulses will be generated by contact 1 of the P relay. In addition, there will be locked up in group 0 the relay ITS1. This contact is supplied with battery through segment 7 of ring 2 of distributor DR3, which battery is held on for the interval when brush b3 passes over segment 13 of ring 5, and consequently one more pulse is generated by contact 1 of relay P. Since neither ITS4 nor ITS1 is operated, the battery supplied through segments 8 of ring 2 and 6 of ring 4 will not reach contact 75 1 of relay P, and no pulses will be generated in

addition to the three previously described. This completes the actuation of the indicators in the lower five rows of the display board.

When the distributor brush *b1* of distributor DR3 reaches segment 9 of ring 2, battery from segment 805 is sent over conductor 5 to operate the SRL relay, Fig. 7. The operation of the SRL relay removes ground at its armature 715 from conductor 1005, and this releases all of the storage relays shown in Fig. 10. The operation of relay SRL also removes battery at its armature and break contact 705 from the locking circuit of the SAG relay, Fig. 10, and restores this relay to normal. The operation of the SRL relay at its armature 707 and make contact energizes the coil of switch DGS, thereby advancing the switch wipers to their third position. In this position the wipers apply ground to conductors 05, 06, 07, 08, 09 of cable 122 and operate the relays DGA05 to 09 in the display board. The advancement of the switch has similarly removed ground and released relays DGA00 to 04.

During the revolution of distributor DR3, brush *b2* passed over segment 5 of ring 4 and applied ground over conductor 810, armature 420 and associated break contact of relay RP, Fig. 4, to the winding of the RC relay, Fig. 4. The operation of relay RC prepared a path for the operation of relay RP when the pulse from segment 5 of the distributor DR3 ceased, which path is from battery through the coil of relay RC, make contact and armature of RC, lower coil of RP, conductor 421, make contact and armature 725 of SST, Fig. 7, conductor 726, through the interrupter contact 424 of switch SCS to ground. The operation of relay RP transferred the circuits from the five segments 0 to 4 of ring 2 of distributor DR3 from conductors 0 to 4 of cable 405 to conductors 5 to 9 of the cable.

When distributor DR3 makes its second revolution, the ground from segment 802, ring 1, will be applied to conductors 5 to 9 of cable 405, and in succession those rows of indicators in the record board, Fig. 3, bearing new position numbers 05 to 09 will be selected and the information transferred to the storage relay groups 0 to 4 of Fig. 10. The operation of restoring and resetting the rows 05 to 09 in the display board is similar to that for rows 00 to 04, and this is likewise true with respect to rows 10 to 14. During the second revolution of distributor DR3, segment 5 of ring 4 again supplies ground over conductor 810, but this time through armature 420 and associated make contact of relay RP to the holding winding of relay RP and the stepping magnet of switch SCS. The operation of magnet SCS prepared the switch to advance its wipers to bank terminal 1. The operation of the magnet SCS also removes ground from conductor 726, opening the operating path of relay RP and relay RC so that at the expiration of the pulse over conductor 810 the switch SCS moves to terminal 1 and the relays RC and RP release. This reconnects the segments 0 to 4 of ring 2, distributor DR3, to the conductors 0 to 4 of cable 405, but since the bank A of the switch SCS now rests on terminal 1, the settings of the next five rows of the record board bearing new position numbers 10 to 14 will be selected for transfer to the display board. At the end of the second revolution of distributor DR3, the circuit established through segment 9 of ring 2 advances the switch DGS, Fig. 7, to its fourth position so that rows 10 to 14 of the display board will be connected to the pulsing multiple.

When all the settings of the rows of the record board have been transferred to the display board in the manner described above, a circuit will be closed from ground on the wiper of bank

- 5 B of switch DGS through terminal 730 to conductor 6 of cables 401 and 133, and conductor 341, Fig. 3, to the key release magnet KR, Fig. 2. The operation of the magnet actuates the latch 200 to unlocking position and restores the SEQ button. Restoring button SEQ releases the relay K, Fig. 1, and the relay SST, Fig. 7. The release of relay K releases the keyset relay KS, restoring the incoming line and keyset connecting equipment to normal. The release of relay 15 SST restores the sequencing equipment in the following manner: Removal of ground at armature and make contact 702 of SST releases the start magnet SM3 of distributor DR3, bringing the distributor to rest. The reclosure of armature 735 of SST with its break contact restores the ground from the interrupter contact 734 of switch magnet DGS to the homing bank A, and by means of the self-interrupting circuit this homing switch buzzes to its home position on terminal 721. The opening of the circuit at armature and make contact 725 of SST releases the RC and RP relays, and transfers the ground from interrupter contact 424 of the sequence collection switch SCS, Fig. 4, to the brush and homing bank B over conductor 430. The switch SCS then has a self-interrupting path completed through the strapped terminals of bank B and its interrupter contact so that this switch buzzes to its home position on terminal 0. This restores 20 30 35 the sequencing equipment to normal.

In the flight progress display board illustrated in Fig. 13 only a few rows of indicators are shown as associated with each Fix, such as Fix 1 to Fix 3, whereas in practice there may be many Fix 40 groups, and a great many rows of indicators may be embodied in each of the Fix groups, and the designation strips bearing the Fix markings have to be shifted upwardly and downwardly on the display board, depending upon the number of 45 horizontal rows of indicators or indicator levels assigned to each Fix. Therefore, the Fix designation strips are adjustably mounted on the flight progress display board so that they may be moved upwardly or downwardly and retained in their 50 moved positions by any suitable holding means, such as pins, screws, hooks and the like. When it is desired to include the indicators of another level, for example, level 04 shown in Fig. 13, within the group of indicators assigned to another Fix, such as Fig. 1, the information posted in row 04 and other rows in the same Fix is transferred upwardly, by the multiple row sequencing operation described, and the designation strip is moved to a position intermediate the indicators 55 of levels 04 and 05, it being understood that in practice the adjacent rows of indicators are spaced apart a sufficient distance to permit the insertion of a Fix designation strip between any of the rows.

- 60 65 While the invention has been described in detail with respect to one illustrative example thereof and with reference to a particular use, it will be understood by those versed in the art that various features of the system and apparatus disclosed herein may advantageously be used in widely different types of communication and posting systems and that various modifications and changes may be made without departing from 70 75 the spirit and scope of the invention, and the in-

vention therefore is not limited except as indicated by the scope of the appended claims.

What we claim is:

1. A system for posting information regarding a plurality of different items, comprising a record board having electrical signal storage devices on which information in regard to the items may be stored in random order on the board, a display board having a plurality of indicating devices assignable to different ones of said items for displaying information in regard thereto, said signal storage devices of the record board including means for storing electrical signal conditions for predetermining the serial order in which the various items of information are to be displayed on the display board, and sequencing apparatus including means controlled by said signal storage devices of the record board for obtaining information therefrom and automatically selecting and energizing the indicating devices of the display board to cause them to display in a predetermined serial order on the latter board the items of information stored on the signal storage devices of the record board.

2. A system for posting information regarding a plurality of different items, comprising a record board having electrical signal storage devices on which information in regard to the items may be stored in random order on the board, a display board having a plurality of indicating devices assignable to different ones of said items for displaying information in regard thereto, said signal storage devices of the record board including means for storing electrical signal conditions for predetermining the serial order in which the various items of information are to be displayed on the display board, and sequencing apparatus including means controlled by said signal storage devices of the record board for obtaining information therefrom and automatically selecting and energizing the indicating devices of the display board to cause them to display in a predetermined serial order on the latter board the items of information stored on the signal storage devices of the record board, said sequencing apparatus operating in a manner to cause said information to remain stored on said signal storage devices.

3. A system for posting information regarding a plurality of different items, comprising a record board having electrical signal storage devices on which information in regard to the items may be stored in random order on the board, a display board having a plurality of indicating devices assignable to different ones of said items for displaying information in regard thereto, said signal storage devices of the record board including means for storing electrical signal conditions for predetermining the serial order in which the various items of information are to be displayed on the display board, other signal storage means, sequencing means controlled by said signal storage devices of the record board for obtaining the stored information from a plurality of said devices successively and storing such information temporarily in said other storage means, and means controlled by said other storage means for concurrently energizing a plurality of the indicating devices of the display board to cause them to display in a predetermined serial order on the latter board the items of information stored on the signal storage devices of the record board.

4. A system for posting information regarding a plurality of different items, comprising a record board in which information in regard to the

items may be stored in random order, said record board having a plurality of electro-responsive storage devices in groups respectively assignable to different ones of said items for storing electrical signal conditions representing the designation of an item and information in regard to the item, a display board having a plurality of electro-responsive indicating devices in groups respectively assignable to different ones of said items for displaying information in regard thereto, said signal storage devices of the record board including means for storing electrical signal conditions for predetermining the serial order in which the various items of information are to be displayed on the display board, and sequencing apparatus including means controlled by said storage devices of the record board for automatically selecting and energizing the indicating devices of the display board to cause them to display in a predetermined serial order on the latter board the items of information stored on the signal storage devices of the record board.

5. A system for posting information regarding a plurality of different items, comprising a display board having a plurality of groups of indicating devices, the groups being respectively assignable to different ones of said items for displaying information in regard thereto, a record board on which information in regard to the items may be stored in random order, said record board comprising a plurality of groups of signal storage devices, the groups being respectively assignable to different ones of said items for storing electrical signal conditions representing the designation of an item and information in regard to the item, said signal storage devices including means for storing electrical signal conditions for predetermining the serial order in which the various items of information are to be displayed on the display board, and sequencing apparatus including means controlled by said signal storage devices for selectively energizing the indicating devices of the display board to cause them to display in predetermined serial order the items of information stored on the storage devices of the record board.

6. A system for posting information regarding a plurality of different items, comprising a display board having a plurality of groups of indicating devices, the groups being respectively assignable to different ones of said items for displaying information in regard thereto, a record board on which information in regard to the items may be stored in random order, said record board comprising a plurality of groups of signal storage devices, the groups being respectively assignable to different ones of said items for storing electrical signal conditions representing the designation of an item and information in regard to the item, said signal storage devices including means for storing electrical signal conditions representing the present positions in which the items are posted on the display board and the new positions to which the items are to be transferred on the display board, and sequencing apparatus including means controlled by said signal storage devices for selectively energizing the indicating devices of the display board to transfer the items of information from their present positions on the display board to new positions thereon and display them in predetermined serial order.

7. A system for posting information regarding a plurality of different items, comprising a record board having electrical signal storage indicators on which indicia representing information in regard to the items may be stored and dis-

played in random order on the board, a display board having groups of electrical indicators assignable to different ones of said items for displaying indicia representing information in regard thereto, said signal storage indicators of the record board including indicators for storing electrical signal conditions for predetermining the serial order in which the various items of information are to be displayed on the display board, and sequencing apparatus including means controlled by said signal storage indicators of the record board for generating and transmitting signals for automatically selecting and energizing the indicating devices of the display board to cause them to display in a predetermined serial order on the latter board indicia representing the items of information stored and displayed on the signal storage indicators of the record board.

8. A system for posting information regarding a plurality of different items, comprising a record board having groups of electrical signal storage indicators on which indicia representing information in regard to the items may be stored and displayed in random order on the board, a display board having groups of electrical indicators assignable to different ones of said items for displaying indicia representing information in regard thereto, said signal storage indicators of the record board including indicators for storing electrical signal conditions for predetermining the serial order in which the various items of information are to be displayed on the display board, a keyset, and sequencing apparatus including means controlled by said keyset and signal storage indicators of the record board for generating and transmitting signals for automatically selecting and energizing the indicating devices of the display board to cause them to display in a predetermined serial order on the latter board indicia representing the items of information stored and displayed on the signal storage indicators of the record board, said sequencing apparatus operating in a manner to cause said information to remain stored on said signal storage indicators.

9. A system for posting information regarding a plurality of items, comprising a record board having settable storage devices responsive to incoming signals for storing electrical signals comprising information in regard to the items, a display board having a plurality of settable indicating devices assignable to different ones of said items for displaying information in regard thereto, settable devices for storing electrical signal conditions for predetermining the serial order in which the various items of information are to be displayed on the display board, and sequencing apparatus controlled by said last named settable devices for automatically generating and transmitting signals for selecting and resetting the indicating devices of the display board to positions to display thereon in a predetermined order the items of information stored on the record board, said sequencing apparatus operating to reset simultaneously a multiplicity of said indicating devices respectively assigned to different ones of said items.

10. A system for posting information regarding a plurality of different items, comprising a record board having rows of signal storage devices, each row being assignable at random to different ones of said items for storing information in regard thereto, a display board having a plurality of rows of indicators, the rows being assignable to different ones of said items for displaying information

in regard thereto, sequencing apparatus for rewriting the display board comprising new position storage devices settable to different positions for predetermining the particular rows of indicators in the display board on which the desired information is to be rewritten, each of said new position storage devices being operatively associated with a particular row of storage devices in the record board, said sequencing apparatus including means controlled by the signal storage devices of the record board and said new position storage devices for automatically selecting certain rows of indicators in the display board and actuating the indicators of the selected rows to cause them to display in a predetermined serial order selected ones of the items of information stored on the signal storage devices of the record board.

11. In a system for posting information regarding a plurality of different items, a record board having a plurality of groups of electrical storage devices on which indicia representing item identification and item information may be stored, and means responsive to incoming signals for finding and actuating the storage devices of a particular one of said groups in accordance with the identification and information represented by the signals, said means including item locator apparatus having means for comparing simultaneously the settings of all the various item identification storage devices of the said groups with the identification data of the incoming signals.

12. In a system of the character described, a display board having groups of electrical indicators on which different items of information are displayed in predetermined serial order, and means for rewriting the board to change the order in which the items are displayed, comprising a plurality of means for concurrently storing signals representing the present locations of a plurality of the items on the display board, a plurality of signal storage means concurrently settable for preselecting the new positions to which the plurality of items of information on the display board may subsequently be transferred, and sequencing means controlled by both of said signal storage means for automatically resetting a plurality of groups of said indicators simultaneously.

13. A system for posting information regarding a plurality of aircraft, comprising a record board having groups of signal storage devices, each group being assignable at different times to different flights respectively of said aircraft, said storage devices being arranged in groups classified in regard to fixes traversed by the aircraft in flight, each group including a plurality of storage devices respectively actuatable to different settings for storing the fix designation, the identification of the aircraft and information in regard to said aircraft, means for setting any of said fix storage devices to designate a given fix, means for setting any of said flight identification storage devices to designate a given flight, and means responsive to incoming fix and flight designation signals for finding the group of storage devices assigned to a particular flight and in a particular fix group, said means including flight locator apparatus having relays respectively controlled by the settings of said fix and flight identification storage devices, and circuit connections controlled by said relays for comparing simultaneously the settings of all the various fix and flight designation storage devices of said groups

with the fix and flight identification data of the incoming signals.

14. A system for posting information regarding a plurality of aircraft, comprising a record board having groups of signal storage devices, each group being assignable at different times to different flights respectively of said aircraft, said storage devices being arranged in groups classified in regard to fixes traversed by the aircraft in flight, each group including a plurality of storage devices respectively actuatable to different settings for storing the fix designation, the identification of the aircraft and information in regard to said aircraft, means for setting any of said fix storage devices to designate a given fix, means for setting any of said flight identification storage devices to designate a given flight, and means responsive to incoming fix and flight designation signals for finding the group of storage devices assigned to a particular flight and in a particular fix group, said means including flight locator apparatus having relays respectively controlled by the settings of said fix and flight identification storage devices, circuit connections controlled by said relays for comparing simultaneously the settings of the various fix and flight designation storage devices of the groups with the fix and flight identification data of the incoming signals, a display board having groups of electrical indicators on which the information relating to the different flights is displayed, present position storage devices respectively associated with the groups of storage devices in the record board, and means controlled by said present position storage devices for selecting the group of indicators in the display board where information in regard to the flight is displayed.

15. A system for posting information regarding a plurality of aircraft, comprising a record board having groups of signal storage devices,

each group being assignable at different times to different flights respectively of said aircraft, said storage devices being arranged in groups classified in regard to fixes traversed by the aircraft in flight, each group including a plurality of storage devices respectively actuatable to different settings for storing the fix designation, the identification of the aircraft and information in regard to said aircraft, means for setting any of said fix storage devices to designate a given fix, means for setting any of said flight identification storage devices to designate a given flight, and means responsive to incoming fix and flight designation signals for finding the group of storage devices assigned to a particular flight and in a particular fix group, said means including flight locator apparatus having relays respectively controlled by the settings of said fix and flight identification storage devices, circuit connections controlled by said relays for comparing simultaneously the settings of the various fix and flight designation storage devices of the groups with the fix and flight identification data of the incoming signals, means including a circuit connection through said fix and flight identification storage devices for selecting the group of information storage devices of the record board, a display board having groups of electrical indicators on which the information relating to the different flights is displayed, sequencing means for rewriting the display board to change the order in which the flights are displayed thereon, said sequencing means comprising sequencing storage devices, and means comprising said circuit connection through said flight identification storage devices for setting said sequencing storage devices in accordance with the information displayed on the storage devices of the record board.
